HARRY A. DOUGLAS, OF BRONSON, MICHIGAN.

DOOR-LATCHING MECHANISM.

Application filed February 23, 1927. Serial No. 170,352.

My invention relates to door latching mechanism and has a number of objects and advantages in view, the device of my invention being of particular use upon the doors of automobiles, though the invention is not to be limited to any particular use.

In accordance with one feature of the invention, a latch bolt is employed in conjunction with a handle for operating it and a coupling member for normally coupling the latch bolt with the handle and adjustable by suitable mechanism into uncoupling position whereby the operative connection between the latch bolt and handle is broken so that if the latch bolt is in engagement with the complementary catch, the door will be locked closed. A key operated lock may be employed for locking the coupling member in uncoupling position so that the handle can not regain control of the latch bolt until the key operated lock is adjusted by the key to restore the coupling member to its handle and latch bolt coupling position. It is understood, of course, that the key operated lock is accessible from the exterior of the automobile or other automotive vehicle. One such structure is usually provided upon an automobile, and on the right hand fore door thereof. Each remaining door is provided with a similar mechanism rearranged to be controlled from within the vehicle. The locking means for holding the coupling member out of coupling relation with the handle and latch bolt, when controlled from within the vehicle, need not be key operated but is controlled by some readily manually operable means, such as a plunger.

The invention has for another object, the provision of means for taking up the wear between the latch bolt and the catch engageable thereby so that the door will not rattle when it is closed. Means are employed for maintaining the latch bolt and catch yieldingly in engagement, this means being desirably in the form of a coiled spring that operates upon the bolt for this purpose. The bolt is desirably mounted to turn and when thus arranged, I desirably slope the catch engaging surface of the latch bolt obliquely of the axis of movement of the bolt so that as wear proceeds, a new place of engagement of the bolt and latch will be found automatically.

I will explain my invention more fully by reference to the accompanying drawings in which Fig. 1 is a side elevation of the

preferred form of latching mechanism, a portion of the door structure being broken away; Fig. 2 is a sectional view on line 2-2 of Fig. 1; Fig. 3 is a sectional view on line 3-3 of Fig. 1; Fig. 4 is a sectional view on line 4-4 of Fig. 3; Fig. 5 is a an edge view of a portion of a door where the latching mechanism is located; Fig. 6 is a sectional view on line 6-6 of Fig. 3; Fig. 7 is a sectional view on line 7-7 of Fig. 3; Fig. 8 is a sectional view on line 8-8 of Fig. 7; Fig. 9 is a perspective view illustrating a spring barrel, a latch bolt, the bolt operating shaft, and the tumbler barrel of a lock, in separated relation; Fig. 10 illustrates the preferred embodiment of the invention adapted to be operated without the aid of the key; Fig. 11 is a side view of a portion of an automobile illustrating one use of the lock of my invention; Fig. 12 is a longitudinal sectional view of another embodiment of the invention; Fig. 13 is a sectional view on line 13-13 of Fig. 12; Fig. 14 is a sectional view on line 14-14 of Fig. 12; Fig. 15 is a perspective view of a spring barrel and cap shown in separated relation; and Fig. 16 is a perspective view of a shaft.

In the embodiment of the invention shown in Figs. 1 to 9 inclusive, the spring barrel 1 is stationarily contained in a recess 2 formed in the door 3 of an automobile, the spring barrel also constituting a spring abutment, as will appear. This door is shown as being mounted upon hinges 4 at one upright side thereof and adapted, when in closed position, to fill the doorway in the surrounding portion of the vehicle body. The door, when closed, is in the plane of the frame 5 surrounding the doorway except for the flange 6 which laps the frame to close the crack between the door and frame, on the outer side of the vehicle. The flange 6 is preferably made of sheet metal and integrally with a shell 7 of the door which contains the filler 8, this filler being cut away to afford the recess 2. The frame 5 is also of sheet metal and is integral with a shell 9 constituting a side of the vehicle body and containing the filler 10, windows, of which one is indicated at 11, being formed through the shell 9 and filler 10. The spring barrel 1 has a reduced annular extension 12 projecting outwardly from the outer end wall 13 of the spring barrel and passing through the shell 7 to the exterior of the door, said spring barrel end wall being held against

the inner face of the adjacent wall of shell 7, as clearly indicated in Figs. 3, 7 and 10. Said spring barrel has another reduced annular extension 14 projecting inwardly 5 from the inner end wall 15 of the spring barrel and terminating to be flush with the inner face of the door, said spring barrel end wall 15 being held against the inner face of the adjacent wall of the shell 7, as clearly 10 indicated in the latter mentioned figures of the drawings. The holes in the shell 7 through which the extensions 12 and 14 pass, snugly receive these extensions and to further hold the spring barrel 1 from movement 15 with respect to the door, the end walls 13, 15 thereof are flattened, as indicated at 13', 15', these flattened portions being in close engagement with the transverse portion 7' of the door shell. To still further 20 hold the spring barrel 1 from movement with respect to the door, the periphery of the portion of the spring barrel extension 14 which is surrounded by the adjacent wall of the door shell 7 is polygonal, as indicated 25 at 14' in Figs. 8 and 9, the opening in this door shell wall being of corresponding contour and snugly receiving the polygonal formation 14'.

The arcuate wall portion of the spring 30 barrel between the end walls 13 and 15 is coaxial with the spring barrel extensions 12 and 14 and the end walls 13 and 15, these end walls being circular except at the flattened portions 13', 15'. A collar 16 is surrounded by the end wall 15 and its extension 14 and is of circular contour where it is surrounded by said extension 14, the opening in this extension that receives said collar being also circular to have bearing fit with 35 said collar to enable the collar to turn and be guided in its turning movement. The bore of the collar 16 is polygonal in contour and is in snug fit with one end of the hollow shaft 17, this shaft end being of corresponding 40 polygonal shape, as indicated at 17', most clearly in Fig. 9. Said shaft is thus journaled, at one end, upon one end wall, 15, of the spring barrel. The other end of this shaft is rotatively supported by the 45 spring barrel extension 12, as will appear. This shaft end projects through the door 3 to the exterior of the door and is there received within the hub 18 of the outer handle 19, the shaft and handle hub being secured in fixed relation by a pin 20. The 50 hub of the handle is journaled upon the in-turned rim portion 12' of the spring barrel extension 12. The latch bolt, hereinafter to be described, is released from door holding 55 engagement by turning the handle 19 on the outer side of the door or by turning the handle 21 upon the inner side of the door, the hub of the latter handle snugly receiving 60 the polygonal end 17' of said shaft. To 65 prevent the handle 21 from being displaced

by movement lengthwise of the shaft, a set screw 22 is screwed into the hub of this handle into engagement with the shaft.

The latch bolt 23 is carried by the intermediate portion 24 of a U-shaped yoke, the 70 ends 25, 26 of the yoke being in the nature of rings through which the shaft 17 is passed. In accordance with an important feature of my invention, means are provided for coupling the latch bolt with and uncoupling it 75 from the bolt operating shaft or member 17. When the bolt is coupled with the shaft, it may be withdrawn from latching position by operating either handle 19 or 21. When the bolt is uncoupled from the shaft, it can 80 not be operated by either handle, the bolt, in effect, being then locked in holding engagement with the V-shaped catch 27 which is contained within the recess 28 formed in the adjacent side of the door frame. The 85 means which I have shown for this purpose resides in a key 29 which passes through diametrically opposite slots 30 in the hollow shaft 17. This key is in the form of a bar which is narrower than the length of 90 said slots to permit the key to be moved bodily longitudinally of the shaft 1 to one position in which it is received within notches 25' formed in the yoke end 25 whereby the latch bolt is coupled with the 95 shaft to turn therewith, and to another position in which the key is removed from said notches to permit the shaft to be turned without turning the latch bolt. Stop lugs 31 are struck inwardly from the end wall 100 13 of the spring barrel into the zone and circle of movement of the key to limit the extent to which the key and the shaft 17 carrying the key may be turned.

The key 29 is adjustable longitudinally of 105 the shaft 17 from the outer side of the door by means of a key controlled locking mechanism in the structure of Figs. 1 to 9. The locking mechanism illustrated includes a rotatable tumbler barrel 32 which is coaxial 110 with and mounted to turn in the handle 19 that receives it. This tumbler barrel includes a number of tumblers 33 movable transversely thereof into and out of the recesses 34 formed in the handle on diametrically opposite sides of the tumbler barrel, these tumblers serving to hold the tumbler barrel in either of two diametrically opposite 115 positions with respect to handle 19 and to which positions the tumbler barrel may be placed by turning the lock key 35 a half turn each time the tumbler barrel is to be brought to a new position, the inserted lock key withdrawing the tumblers from the recesses 34 to permit the tumbler barrel to be 120 turned. The tumbler barrel is locked into selected fixed relation with the handle 19 when the tumblers are brought into register with the recesses 34 and following the withdrawal of the lock key 35. When the tum- 130

bler barrel is turned to the position shown in Fig. 3, the ends of the key 29 enter the notches 25' whereby the handles and shaft are coupled and enabling the latch bolt to be withdrawn from engagement with the catch when either handle 19 or 21 is turned, whereafter the lock key 35 may be withdrawn to permit the tumblers to enter recesses 34. The tumbler barrel is turned 10 180 degrees from the position shown in Fig. 3 in order to withdraw the key 29 from said notches 25' so that either handle may be turned without withdrawing the latch bolt 23 from the catch 27. When the tumbler barrel is brought to this position, the tumblers may again enter the recesses 34, following the withdrawal of the lock key 35, so that the key 29 is locked out of engagement with the notches 25', thereby locking 15 the handles out of actuating relation with the bolt. If the bolt is in engagement with the catch, the door 3 is thus locked shut. The means shown through which the tumbler barrel operates upon the key 29 is inclusive of a bar 36 which is slidingly received in the bore of the shaft 17 and through which bar the key 29 is passed, this key and bar being in fixed relation at one end of the bar. The key 29 has snug sliding fit within the slots 30 so that the bar and shaft may turn together. The other end of the bar carries a pin 37 which rides upon the cam portion 38 at the inner end of the tumbler barrel 32. A coiled spring 39 is contained within the bore of the shaft 17, one end of this spring engaging the abutment screw 40 which is screwed in one end of the shaft, the other end of this spring pressing upon the bar 36 to hold the pin 37 against the cam 38, the cam, pin, and spring cooperating to define the longitudinal position of the bar and the key 29 carried by the bar.

Another important characteristic of my invention resides in the provision of means for holding the latch bolt 23 and the catch 27 in engagement in a manner to compensate for any wear of these parts that would otherwise permit them to be loosely engaged and thereby permit the door to rattle. In accordance with this feature of my invention, means are provided for yieldingly pressing one of the elements 23, 27 against the other while these two elements are in holding relation. I have employed a coiled spring 41 for this purpose, this spring incidentally surrounding the shaft 17 and having one end anchored upon the spring barrel 1 at 1' and having its other end in engagement with the yoke portion 24 at 24'. This spring is constantly under tension which is sufficient to maintain the latch bolt 23 in firm engagement with the catch 27 when the door is closed thereby compensating for any wear upon these parts 23 and 27. The latch

bolt 23 and its supporting yoke 24, 25, 26 is free to be turned within the spring barrel 1 by said spring throughout a sufficient range whose limit is desirably defined by means of lugs 42 upon the yoke ends 25, 70 26. Fig. 4 shows the spring 41 functioning to hold the latch bolt in full engagement with the catch, this figure showing sufficient clearance between the lugs 42 and the adjacent portions of the spring barrel to permit further movement of the latch bolt in a clockwise direction in the event of additional wear. The surface of the bolt 23 that engages the catch 27 is preferably oblique to the axis of rotation of the bolt to further assure the maintenance of engagement of these two elements. The spring 41, in addition to performing the functioning which has been described for it, also serves as a means for permitting the bolt 23 to automatically have latching engagement with the catch 27 when the door is being brought to a closed position. When the door is being closed, the latch bolt will ride upon the inclined surface 27' of the V-shaped catch 27 90 and will slip behind the catch into holding engagement with the holding surface thereof that forms a V with the surface 27', Fig. 2, the tension of the spring 41 increasing as the bolt rides upon the catch surface 27' and partially yielding when the bolt is in holding engagement with the catch.

The latching mechanism of my invention that is supplied with the key operated locking mechanism described is desirably provided upon the right hand fore door of an automobile. This latching mechanism, unprovided with the key operated mechanism, may be provided in connection with each of the other doors in which event it is furnished with means operable from within the automobile for coupling the latch bolt with and uncoupling it from the operating shaft so as to permit the latch bolt to be operated or prevent it from being operated by the corresponding handle on the exterior of the automobile. Such an arrangement is illustrated in Fig. 10 where the operating handle 19' upon the exterior of the automobile is unprovided with a key controlled locking mechanism but which is adapted to be coupled with the operating shaft in a manner similar to that in which the handle 19 is coupled with the operating shaft. Parts illustrated in Fig. 10 which are similar to parts elsewhere illustrated are given similar characters of reference. In Fig. 10, the bar 36' replaces the bar 36 and the coiled spring 39' replaces the coiled spring 39. The key 29 passes through the bar 36' and is related to the shaft 17, as in the key controlled lock structure previously described. The spring 39' presses the bar 36' inwardly to maintain the key 29 in the notches 25', this spring being bottomed upon and within the handle 130

19'. In order that the key 29 may be placed in an uncoupling position from within the automobile, I provide a plunger 43 having a thumb piece 43' thereon whereby it may be pressed inwardly, this plunger engaging one end of the bar 36' whereby this bar may be moved sufficiently to place the key 29 out of the zone of the yoke end 25. This plunger is provided with a bayonet slot 44 in its side 10 that receives a pin 45 fixed upon the shaft 17 and projecting from the shaft into said bayonet slot. When the handle 19' is to be given control of the latch bolt, the parts are in the adjustment as illustrated in Fig. 10 15 but when the handle 19' is to be uncoupled from the latch bolt, the plunger 43 is depressed until the transverse branch of the bayonet slot is in register with the pin where- 20 after the plunger is turned to cause the transverse branch of the bayonet slot to receive the pin whereby the key 29 is locked outside of the zone of the yoke end 25 to maintain the handle 19' uncoupled from the latch bolt. The handle 19', as in the case of 25 the handle 19, is free to turn when the key 29 is in uncoupling position. The degree of turning movement of the handle is limited by such lug formations as indicated at 31 in Fig. 6. It is understood that the handle 30 21, in the structure of Fig. 10, is coupled or uncoupled with the bolt when handle 19' is so coupled or uncoupled. In both forms of the invention hitherto described, the larger portion of collar 16 prevents the key 29 from 35 being entered into the notches 25' by inwardly pushing the handle 19 or 19'.

The form of the invention illustrated in Figs. 12 to 16 inclusive has many features in common with the structures hitherto described, like parts being given similar characters of reference. In this third form of the invention the shaft 17² serves the purpose of the shaft 17, but is in the form of a hollow hexagonal tube, instead of being cylindrical. This shaft 17² is surrounded by a stationary sleeve 16' which has notches 16² formed in one end thereof in which the key 29 is constantly received in either adjustment thereof, this key playing in the slots 30 and being movable into and out of the notches 25' as in the case of the other embodiments of the invention. The notches 16² are wide enough to permit the shaft 17² to turn throughout its arcuate 55 range of movement. The sleeve 16' is formed with an annular bead 16³ which has a notch 16⁴ therein that receives the tongue 15² carried by the wall 15 of the spring barrel 1. As this spring barrel is stationary, the sleeve 16' is thus held from rotation. The sleeve is held from axial movement by means of a second bead 16⁵ engaging the outer face of the barrel end wall 15 and which draws the bead 16³ tightly against the 60 inner face of this wall. The cap 13² com-

pletes the spring barrel at the end thereof which is opposite the end wall 15. The cap may be suitably held in position as by spot welding. The shoulder 12² upon this cap engages an adjacent shoulder, Figs. 12 and 70 14, upon the hub of the handle 19 so that this handle can not be thrust inwardly to defeat the purpose of the latch. In each form of the invention illustrated, the holding surface of the bolt slopes, from the side 75 thereof that initially engages the holding surface of the catch, toward the riding surface of the catch, when the holding surfaces of the bolt and catch are in engagement, whereby said spring is adapted to effect 80 compensation for wear upon either of said holding surfaces. The holding surface of the latch thus laps the catch when the latch and catch are in holding engagement.

Changes may be made without departing 85 from the invention.

Having thus described my invention, I claim:

1. Latching mechanism including a latching bolt mounted to turn and having a holding surface oblique to the axis of the bolt; a catch having a holding surface and a riding surface angular to the holding surface, said bolt being arranged to ride upon and clear said riding surface to bring its holding 90 surface into engagement with the holding surface of the catch; a spring pressed upon by the bolt when the bolt rides upon said riding surface and serving to turn the bolt and press the holding surface thereof upon 95 the holding surface of the catch when the bolt clears the riding surface of the catch; a stationary barrel containing said spring and upon which one end of the spring is anchored, the other end of the spring engaging 100 the bolt; a shaft coaxial with the bolt; a member for coupling the shaft and bolt and adjustable into coupling and uncoupling positions; a handle upon the shaft; and a locking device in controlling relation 105 to said coupling member.

2. Latching mechanism including a latching bolt mounted to turn and having a holding surface oblique to the axis of the bolt; a catch having a holding surface and a riding surface angular to the holding surface, said bolt being arranged to ride upon and clear said riding surface to bring its holding 110 surface into engagement with the holding surface of the catch; a spring pressed upon by the bolt when the bolt rides upon said riding surface and serving to turn the bolt and press the holding surface thereof upon 115 the holding surface of the catch when the bolt clears the riding surface of the catch; a stationary barrel containing said spring and upon which one end of the spring is anchored, the other end of the spring engaging the bolt; a shaft coaxial 120 with the bolt; a member for coupling the shaft and bolt and adjustable into coupling and uncoupling positions; a handle upon the shaft; and a locking device in controlling relation 125 to said coupling member.

shaft and bolt and adjustable into coupling and uncoupling positions; a handle upon the shaft; and a locking device having a key operated member in controlling relation to said coupling member.

3. Latching mechanism including a latching bolt mounted to turn and having a holding surface oblique to the axis of the bolt; a catch having a holding surface and a riding surface angular to the holding surface, said bolt being arranged to ride upon and clear said riding surface to bring its holding surface into engagement with the holding surface of the catch; and a spring pressed upon 10 by the bolt when the bolt rides upon said riding surface and serving to turn the bolt and press the holding surface thereof upon the holding surface of the catch when the bolt clears the riding surface of the catch, 15 the holding surface of the bolt sloping, from the side thereof that initially engages the holding surface of the catch, toward the riding surface of the catch, when the holding surfaces of the bolt and catch are in 20 engagement.

4. Latching mechanism including a latching bolt mounted to turn; a catch positioned to be engaged by the bolt when the bolt is turned in one direction and to be freed of 25 holding engagement with the bolt when the bolt is reversely turned, the holding surface of the bolt being oblique to the axis of the bolt; and spring means pressing upon the bolt in a turning direction to maintain said 30 oblique holding surface of the bolt in holding engagement with the catch, the holding surface of the bolt sloping, from the side thereof that initially engages the catch, in 35 a direction to lap the catch when the bolt and catch are in holding engagement.

5. Latching mechanism including a latching bolt mounted to turn; a catch positioned to be engaged by the bolt when the bolt is turned in one direction and to be freed of engagement with the bolt when the bolt is re- 40

versely turned, the holding surface of one of the aforesaid elements being oblique to the axis of said bolt and lapping the holding surface of the other element when the bolt and catch are in holding engagement; and 50 spring means pressing one of the aforesaid elements in holding direction upon the other when these elements are in latching engagement.

6. Latching mechanism including a latching bolt mounted to turn; a V-shaped catch upon one of whose V forming surfaces the bolt is adapted to ride clear thereof into holding engagement with the other of such surfaces; and a spring in turning relation to 60 the bolt and pressed upon by the bolt when the bolt is riding upon the first aforesaid surface of the catch and pressing the bolt upon the second aforesaid surface of the catch when the bolt clears the first aforesaid 65 surface of the catch.

7. Latching mechanism including a latching bolt; a V-shaped catch upon one of whose V forming surfaces the bolt is adapted to ride clear thereof into holding engagement 70 with the other of such surfaces; and a spring in moving relation to the bolt and pressed upon by the bolt when the bolt is riding upon the first aforesaid surface of the catch and pressing the bolt upon the second aforesaid 75 surface of the catch when the bolt clears the first aforesaid surface of the catch.

8. Latching mechanism including a latching bolt; a catch engageable by the bolt; a shaft in turning relation to the bolt; a handle for turning the shaft; a coupling member for coupling the handle and shaft; cam mechanism governing said coupling member; and locking mechanism operable upon 80 said cam mechanism to place the coupling member in uncoupling position.

In witness whereof, I hereunto subscribe my name.

HARRY A. DOUGLAS.
